UNITED STATES PATENT OFFICE.

GEORGE H. CROWELL, OF BERLIN, NEW HAMPSHIRE.

OIL BURNER.

Application filed March 6, 1926. Serial No. 82,776.

This invention relates to improvements in oil burners and is particularly directed to burners such as are installed in residential heating systems for burning oil instead of 5 coal or other solid fuel.

It is an object of the invention to provide such an oil burner with means whereby the admission of air to the burner through the air manifold will be automatically and accurately controlled, so that in each position of adjustment there will be correct and proportionate volume of air with respect to the amount of oil supplied to the burner.

Another object of the invention is to provide means for imparting a whirling motion to a portion of the incoming air so that a more intimate and thorough mixture of the air and oil will be obtained.

With these and other objects in view, my invention consists in the construction, arrangement and combination of the various parts of the burner, whereby the objects contemplated are attained, as hereinafter more fully set forth, pointed out in the appended claims, and illustrated in the accompanying drawings, in which:

Figure 1 is a cross sectional view of a portion of a furnace showing the burner installed therein;

Fig. 2 is a plan view of the burner detached from the furnace;

Fig. 3 is a top plan view of the burner disc, and

Fig. 4 is an inverted plan view of the burner disc.

In the drawings, the numeral 1 represents a domestic furnace adapted for heating either by hot air, hot water, or steam, having the usual ash pit 2, and grate bars 3. 40 Mounted on the floor of the ash pit is a supporting base 4, having a plurality of upstanding apertured bosses, or projections 5 into which standards 6, forming a support for the burner base 7, are threaded. The 45 standards 6 support the burner base 7 in place upon the grate bars 3, for which purpose the burner base is provided with a projecting flange 8 having threaded bosses or projections 9, into which the standards 50 6 are threaded. To provide for the proper seating of the burner base 7 upon grate bars of different makes of furnaces in which the height of the grate bars from the floor of the ash pit vary, the standards 6 have their 55 ends which screw into the bosses or projections 5 and 9 threaded for a considerable

distance. It will thus be readily understood that by screwing the standards 6 into the bosses or projections 5 and 9 varying distances, the burner base 7 may be properly seated upon the grate bars of any make of furnace. The threading of the standards 6 into the bosses 5 and 9 will provide for an approximate leveling of the burner base 7, but a minute leveling of the 60 burner base cannot be readily obtained in this manner. To provide for such a minute leveling of the burner base 7 the supporting base 4 is provided with a plurality of leveling screws 10 adapted to overcome any 65 unequal adjustment of the standards 6, or any unevenness of the floor of the ash pit.

Located centrally of the burner base 7 is an aperture 11 over which is placed a horizontal burning disc 12, which may be 70 formed integral with the burner base 7, but preferably, for purposes of construction, formed of a separate piece removably secured to the base by means of bolts 13, or the like. The burner disc 12 is provided at 75 its outer periphery with an upstanding flange 12' adapted to retain any unvaporized oil upon the disc until vaporization and combustion take place. On diametrically opposite sides of the burner disc 12 the base 80 7 is provided with apertures 14 and 15, which communicate with a manifold 16 having a downwardly disposed aperture 17 therein through which air communicated to 85 said manifold through the apertures 14 and 13 is distributed onto the upper surface of the burner disc 12 supported on the base 6 beneath said manifold. The oil is supplied to the burner disc 12 by means of a supply 90 pipe 18 having a suitable control valve 19. The supply pipe 18 extends beneath the base 100 7 and passes upwardly through the burner disc 12 at a point slightly to one side of the center thereof. In order that the oil which is supplied slightly to one side of the center 105 of the disc may be evenly distributed over its upper surface, the disc is provided with a semi-circular rib 20, having its open side toward the center of the disc. The rib 20 causes a greater portion of the oil to be 110 directed toward the side of the disc opposite the rib and thereby causes an even distribution and burning of the oil over the entire surface of the disc 12.

If the maximum efficiency is to be obtained from a burner of this character it is essential that the volume of air supplied to

the burner through the manifold 16 be accurately proportioned with respect to the amount of oil supplied to the burner, so as to obtain a complete combustion of all of the oil. To provide for the correct volume of air being admitted to the burner regardless of how the oil supply valve 19 may be adjusted, an automatic regulation of the air supply is provided. The supporting base 4 has projecting from one side thereof the extension 21, having secured at its outer end the upright member 22 provided with an elongated opening 23. Pivoted to the extension 21 between the base 4 and the upright 22, is a second upright 24 which acts as a fulcrum for a valve adjusting lever 25. The inner end of the lever 25 is pivotally connected to a valve rod 26 which passes upwardly through the center of the burning disc 12 and the downwardly disposed aperture 17 and out through the top of the manifold 16. Located within the manifold 16 and carried by the rod 26 is a conical valve 27, adapted to control the passage of air through the downwardly disposed aperture 17 of the manifold 16 to the burning disc 12. The outer end of the lever 25 extends beyond the upright 22 and has pivoted thereto the upright link 28, which is adjustably secured at its upper end 29 to a rod 30 rigidly carried by the oil supply valve operating means. To steady the lever 25 in its operation it is provided with a projecting pin, or the like, 31, which passes through the elongated opening 23 in the upright 22, which is retained therein by means of a head 32. When the burner is installed in the furnace, the conical valve 27 will be set to admit, from the manifold 16, the correct volume of air with respect to the amount of oil supplied to the burner. Thereafter any adjustment of the valve 19 will cause an oscillatory movement of the link 30, which movement will be transmitted through the upright 28, lever 25 and rod 26 to the air regulating valve 27, thereby causing the opening or closing of the aperture 17 a sufficient amount to maintain the established proportion between air and oil. As thus far described the air for supporting combustion of the oil is admitted to the manifold 16, from which it is directed downwardly through the aperture 17 onto the top of the burning disc 12. It has also been found desirable to admit a portion of the air from beneath the disc 12, and for this purpose the disc is slightly spaced from the base 7 to provide an annular opening 33 through which the additional supply of air passes. It has also been found desirable, in order to hold the air in contact with the oil longer and to cause a muffling of the noise, to give the air entering the combustion chamber through the opening 33 a whirling motion. To this end the lower

face of the disc 12 has formed thereon a plurality of spiral vanes 34 through which the air must pass before entering the combustion chamber through the annular opening 33, and which impart the necessary 70 whirling motion to the air to hold it in contact with the oil on the upper surface of the disc 12, a sufficient length of time to enable complete combustion.

No means is provided for regulating the 73 amount of air which passes through the annular opening 33, as it has been found that an automatic regulation of the volume of air which passes through the downwardly disposed aperture 17 onto the top 80 surface of the burning disc 12 is sufficient to maintain the established proportion of air and gas.

Although the invention has been described with reference to a particular combination and arrangement of parts, it is to be understood that the invention is not so limited, but that any changes within the scope of the appended claims may be made without departing from the spirit of the 85 invention.

I claim:

1. In a fluid fuel burner, a burning surface, means for supplying fuel to said surface, means for varying the amount of fuel supplied, a manifold through which air passes downwardly onto said surface, and means within and cooperating with said manifold for varying the volume of air passing through the manifold, said means 95 being positioned adjacent the air outlet of the manifold and centrally disposed with respect to the burning surface. 100

2. In a fluid fuel burner, a burning surface, means for supplying a variable supply of fuel to said surface, a manifold having an outlet above the burning surface, a reciprocating valve within said manifold adjacent the outlet thereof around which the air passes downwardly onto the burning surface, and means for adjusting the valve with respect to the manifold to vary the volume of air passing out of said manifold. 105 110

3. In a fluid fuel burner, a burning surface, means for supplying fuel to said surface, means for varying the amount of fuel supplied, a manifold having an outlet above the burning surface, a reciprocating valve within the manifold adjacent the outlet thereof around which air passes downwardly onto the burning surface, and means for simultaneously adjusting the valve with respect to the manifold as the supply of fuel is varied to automatically regulate the volume of air passing out of said manifold. 115 120

4. In a fluid fuel burner, a burning surface, means for supplying fuel to said surface, means for varying the amount of fuel supplied, a manifold having an outlet above the burning surface, a reciprocating valve 125

- within the manifold adjacent the outlet thereof around which air passes downwardly onto the burning surface, means independent of said manifold for supplying an additional amount of air to said burning surface from beneath, and means for simultaneously adjusting the valve with respect to the manifold to vary the volume of air supplied to the burning surface through the manifold.
5. In an oil burner, a burner plate having a substantially flat surface and an oil conduit extending therethrough at one side only, means for supplying oil through said conduit to said burner plate, and means between said conduit and the side of the plate adjacent thereto for causing a substantially even distribution of the oil over said plate.
6. In an oil burner, a burner plate having a substantially flat surface and an oil conduit extending therethrough at one side thereof only, means for supplying oil through said conduit to said burner plate, and a curved projection on one side of said burner plate for causing a substantially even distribution of the oil over the surface thereof.
7. In an oil stationary burner, a combustion chamber, a burner disc on which combustion takes place, means for supplying oil to said burner disc, means for admitting air to the combustion chamber and means on the lower surface of said disc for imparting a whirling motion to the air.
- 30 8. In an oil stationary burner, a combustion chamber, a burner disc on which combustion takes place, means for supplying oil to said disc, means for admitting air to the combustion chamber from beneath the burner disc, and spiral vanes on the lower surface of said disc for imparting a whirling motion to the air.
- 40 9. In an oil burner, a combustion chamber, a burner disc on which combustion takes place, means for supplying oil to said disc, means for supplying air to the combustion chamber from above the burner
- disc, means for admitting air to the combustion chamber from beneath the burner disc, and means for imparting a whirling motion to the air admitted from beneath the burner disc.
5. In an oil burner, a combustion chamber, a burner disc on which combustion takes place, means for supplying oil to the combustion chamber from above said burner disc, means for admitting air to the combustion chamber from beneath the burner disc, and means on the lower surface of said burner disc for imparting a whirling motion to the air admitted from beneath the burner disc.
10. In an oil burner, a combustion chamber, a burner disc on which combustion takes place, means for supplying oil to the combustion chamber from above said burner disc, means for admitting air to the combustion chamber from beneath the burner disc, and means on the lower surface of said burner disc for imparting a whirling motion to the air admitted from beneath the burner disc.
11. In an oil burner, a combustion chamber, a burner disc on which combustion takes place, means for supplying oil to said disc, a manifold for supplying air to the combustion chamber from above the burner disc, means for admitting air to the combustion chamber from beneath the burner disc, and spiral vanes on the lower surface of said burner disc for imparting a whirling motion to the air admitted from beneath the burner disc.
12. In an oil burner, a supporting base having an extension, a combustion chamber, a burning surface, means for supplying oil to said burning surface, a valve for varying the supply of oil, a manifold through which air passes to the combustion chamber, a valve within said manifold and co-operating therewith for automatically varying the amount of air passing therethrough as the oil supply is varied, a rod carrying said air control valve, a link operably connected to the oil supply valve, an upright member secured to the extension of said supporting base, and a lever pivotally connected to said upright member and connected at one end to the rod carrying the air control valve, and at its other end to the link operably connected to the oil supply valve.
- In testimony whereof I affix my signature.
- GEORGE H. CROWELL.

- within the manifold adjacent the outlet thereof around which air passes downwardly onto the burning surface, means independent of said manifold for supplying an additional amount of air to said burning surface from beneath, and means for simultaneously adjusting the valve with respect to the manifold to vary the volume of air supplied to the burning surface through the manifold.
5. In an oil burner, a burner plate having a substantially flat surface and an oil conduit extending therethrough at one side only, means for supplying oil through said conduit to said burner plate, and means between said conduit and the side of the plate adjacent thereto for causing a substantially even distribution of the oil over said plate.
6. In an oil burner, a burner plate having a substantially flat surface and an oil conduit extending therethrough at one side thereof only, means for supplying oil through said conduit to said burner plate, and a curved projection on one side of said burner plate for causing a substantially even distribution of the oil over the surface thereof.
7. In an oil stationary burner, a combustion chamber, a burner disc on which combustion takes place, means for supplying oil to said burner disc, means for admitting air to the combustion chamber and means on the lower surface of said disc for imparting a whirling motion to the air.
8. In an oil stationary burner, a combustion chamber, a burner disc on which combustion takes place, means for supplying oil to said disc, means for admitting air to the combustion chamber from beneath the burner disc, and spiral vanes on the lower surface of said disc for imparting a whirling motion to the air.
9. In an oil burner, a combustion chamber, a burner disc on which combustion takes place, means for supplying oil to said disc, means for supplying air to the combustion chamber from above the burner
- disc, means for admitting air to the combustion chamber from beneath the burner disc, and means for imparting a whirling motion to the air admitted from beneath the burner disc.
10. In an oil burner, a combustion chamber, a burner disc on which combustion takes place, means for supplying oil to the combustion chamber from above said burner disc, means for admitting air to the combustion chamber from beneath the burner disc, and means on the lower surface of said burner disc for imparting a whirling motion to the air admitted from beneath the burner disc.
11. In an oil burner, a combustion chamber, a burner disc on which combustion takes place, means for supplying oil to said disc, a manifold for supplying air to the combustion chamber from above the burner disc, means for admitting air to the combustion chamber from beneath the burner disc, and spiral vanes on the lower surface of said burner disc for imparting a whirling motion to the air admitted from beneath the burner disc.
12. In an oil burner, a supporting base having an extension, a combustion chamber, a burning surface, means for supplying oil to said burning surface, a valve for varying the supply of oil, a manifold through which air passes to the combustion chamber, a valve within said manifold and co-operating therewith for automatically varying the amount of air passing therethrough as the oil supply is varied, a rod carrying said air control valve, a link operably connected to the oil supply valve, an upright member secured to the extension of said supporting base, and a lever pivotally connected to said upright member and connected at one end to the rod carrying the air control valve, and at its other end to the link operably connected to the oil supply valve.

In testimony whereof I affix my signature.

GEORGE H. CROWELL.

CERTIFICATE OF CORRECTION.

Patent No. 1,621,313.

Granted March 15, 1927, to

GEORGE H. CROWELL.

It is hereby certified that error appears in the printed specification of the above numbered patent requiring correction as follows: Page 3, lines 28 and 35, claims 7 and 8 respectively, strike out the word "stationary" and insert the same to follow before the word "burner" in lines 29 and 36, same claims; and that the said Letters Patent should be read with this correction therein that the same may conform to the record of the case in the Patent Office.

Signed and sealed this 12th day of April, A. D. 1927.

Seal.
